UNITED STATES PATENT OFFICE.

WILLIAM ARCHIBALD WOOD, OF MONTREAL, CANADA.

WORKMAN'S TIME-RECORDER.

No. 814,760.

Specification of Letters Patent.

Patented March 13, 1906.

Application filed May 7, 1903. Serial No. 156,073.

To all whom it may concern:

Be it known that I, WILLIAM ARCHIBALD Wood, of the city of Montreal, Province of Quebec, Canada, have invented certain new and useful Improvements in Workmen's Time-Recorders; and I do hereby declare that the following is a full, clear, and exact description of the same.

This invention relates particularly to workmen's time- recorders of the type disclosed in my pending application filed February 3, 1903, under Serial No. 141,766; and it has for its object to adapt said time-recorder to record the time either upon a time-card or time-sheet, as desired.

The invention may be said to consist in combining with the time - sheet - printing means whereby said time-sheet-printing means can be caused to print a time-card, 20 and an auxiliary time-card-printing device whereby the time can be recorded upon a card simultaneously with or at different times to said sheet and card printing means just mentioned.

For full comprehension, however, of my invention reference must be had to the accompanying drawings, forming a part of this specification, in which like symbols indicate the same parts, and wherein—

Figure 1 is a vertical sectional view of my improved time-recorder; Fig. 2, a detail sectional view of a portion of one of the rolls of the time-sheet carrier and illustrating particularly the manner of connecting the ends 35 of the apron. Fig. 3 is a detail view of a portion of the ink-ribbon-shifting gear and the means for retaining the minute-wheel; Fig. 4, a similar view taken at right angles to Fig. 1. Fig. 5 is a side elevation of a portion of the 40 means for retaining the workman's lever against movement.

The workman's lever *b*, the dials *c*, *d*, and *e*, the clockwork *f*, the minute and hour wheels *g* and *h*, respectively, the carriage *i*, in which said time-wheels are mounted, and the operative means *j*, connecting the clockwork to the carriage, are the same as disclosed in my said pending application.

I have improved the means for operating 50 the hour-wheel from the minute-wheel and adapted these wheels to be turned either forward or backward simultaneously with the clock-movement as it is being set. I have also simplified the devices for retaining the 55 minute and hour wheels in their proper printing positions, with the result that besides en-

abling the time-wheels to be turned in either direction less power is required to operate them. The minute-wheel is driven in the usual way by a train of gears *m*, leading from 60 the clock-movement.

My improved connection between the minute and hour wheels consists of a crank *n*, mounted upon the arbor *o* of the minute-wheel and adapted to engage a star-wheel *p*, 65 mounted rigidly upon the hour-wheel. By this means each complete revolution of the minute-wheel rotates the hour-wheel one notch. The hour-wheel is held in the position to which it is moved by the minute- 70 wheel by a latch constituted by a fork ful-

crumed, as at *q*, at its crotch, and having the end *r* of one leg bent transversely of and adapted to engage a notch *s* in the periphery of a disk *t*, mounted rigidly upon the ar- 75 bor *o* of the minute-wheel, while the end of the other leg is bent to form an angular tooth *v*, adapted to engage the points of the star-wheel *p*. The tooth *v* is normally main- 80 tained yieldingly in engagement with the point of the star-wheel by a retractile helical spring 175. As the crank *n* engages the star-wheel *p* the notch *s* allows the fork freedom to be moved. The minute-wheel is adjusted to and held in its proper printing 85 position by a star-wheel *2*, secured rigidly upon one side thereof and adapted to be en- gaged and held during the printing oper- ations by a pawl consisting, preferably, of a bent rod *3*, projecting through a slot 12 in a 90 collar 10 (to be presently described) and se- cured rigidly at its lower end to a short spin- 95 dle 4, journaled in the frame of the carriage. The pawl is operated by the platen (to be presently described) through the medium of a pair of movable bolts 6 and 6^a, connected by a bar 7, upon which the platen acts. The shank of bolt 6 is perforated to receive one end of an arm 9, the opposite end whereof is secured rigidly to said collar 10, which is ro- 100 tatable upon the spindle 4, an expansile spring 11, coiled around the collar, bearing at one end upon the pawl and at its other end upon the arm. The movement of the pawl and rod away from one another is limited 105 and the pawl caused to return to its normal position by the slot 12 in the collar 10 and a helical spring 13, to be presently described. A pair of sleeves 8 and 8^a, carried rigidly by the bar of the ribbon-gear, receive the bolts, 110 and the sleeve 8 is slotted to allow the arm 9 to pass therethrough and accommodate it.

in its movement. The arm is yieldingly kept in its lowermost position and the pawl out of engagement with the star-wheel 2 by a helical spring 13 within the sleeve 12 and bearing between the inwardly-flanged upper end of the sleeve and a shoulder 14 upon the bolt. The upper end of the bolt has a spring-pawl 15, fulcrumed thereto and adapted to engage the ratchet 16 of the ribbon-feed, (indicated at 17, and which may be of ordinary construction.)

According to my present invention the time-sheet carrier is movable bodily toward and from the time-printing wheels and has a platen movable therewith and carried thereby, the platen being preferably located adjacent to one end of the carrier and said carrier being located with the end thereof bearing the platen adjacent to a slot in the casing, through which a time-card may be passed, while the time-printing wheels are located in a position to be borne upon by the platen. This carrier is supported in a frame secured rigidly to the bottom of the case and having two pairs of end legs 21 and 22, respectively, and a pair of intermediate legs 23. A spindle 24 extends between and is journaled in the upper ends of the legs 21, a frame 25 being pivoted at one end upon this spindle and having downwardly-projecting lugs 26, (to be presently further alluded to,) while the platen 27, with a convex side 28, is secured to the top and transversely of this frame and within a short distance of the free end thereof. A spindle 29 is journaled in this end of the frame, a roller 30 being mounted thereon, and a second roller 31 is mounted upon the spindle 24. Four sprocket-wheels 32 are mounted, two upon the spindle 29, one at each end of roller 30, and two upon spindle 24, one at each end of roller 31. These sprockets are rotated in either direction, as in my before-mentioned invention, by endless chains 33, and the time-sheet is carried upon a cushioned flexible impression-apron 34, stretched over the rollers between perimetric guards 35 upon the rollers and adapted to keep the apron straight. The time-sheet 40 is secured upon this apron by a pair of spring-clips 41, carried upon the ends of short bars 42, secured to the sprocket-chains 33. This time-sheet carrier is raised to bring the platen into bearing relation with the time-printing wheels by pressing in the workman's lever *b*, and to effect this the usual slideable spindle 51, around which the workman's lever swings, is caused to bear upon a plate 52, hinged at its lower end, as at 53, to the supporting-frame 54 within the casing. This plate is connected at its upper end by a coiled spring 55 to one end of a slideable bar 56, guided in the supporting-frame 54. A rod 155 is within spring 55 and limits the movement of the ends of this spring toward one another, this slide-bar being connected by a pair of toggle-

bars 57 to the downwardly-projecting lugs 26, before mentioned, while the frame 25 has a pair of antifriction-rollers 58 thereon adapted to run on the inside face of the legs 22, and a retractile spring 59 is connected at one end to the slide-bar 56 and at its other end to the frame 54. If the spindle 51 should happen to be pushed in farther than is necessary to cause the platen to press upon the time-printing wheels, the springs 55 will yield, thus preventing damage to the type upon the time-printing wheels, while the spring 59 will return the bar 56 and with it plate 52 to their normal positions.

The combination of parts just described enables either a time-sheet or a time-card to be printed by the same machine, which is a considerable advantage; but it has been frequently found necessary—where piecework is being done, for instance—to have separate means to time the latter. To combine all the means necessary for this purpose in a single machine is one of the objects of this invention, and I have therefore mounted a second train of time-printing wheels adjacent to the side of the casing opposite to that near which the combined means is located. These auxiliary wheels (indicated at 60 and 61) are connected by a train of gears 62, 63, 64, and 65 to the clockwork mechanism which drives the main time-wheels. The type upon the auxiliary wheels are smaller than those upon the main wheels in order that the cards when printed may be distinguished. The platen 70 in the auxiliary means is carried between the forked inner end 170 of an angular lever fulcrumed at 71 and having its other end 72 projecting outside of the frame. The inner leg 73 of this lever has a guide 74 upon its top, and the casing is slotted, as at 75, in line with said guide 74. The platen is preferably in this case flexible, and the ribbon 76 is fed by similar means as described in connection with the main printing means. In order to enable the workman to print his card in the correct column, I provide a slide-bar 78 supported and guided in a sleeve 79, carried by a bracket 80. A cross-plate 81 upon the inner end of this bar acts as a stop for the card and limits the extent to which it may be inserted. This slideable bar projects outside of the casing and is provided with a thumbhold 83 at its outer end, and its under side is notched, as at 84 and 85, to engage a dog 86, set in a slot 87 in the casing. One of these notches is marked "Out" and the other "In" to guide the workman. A spring 171 returns the lever to its normal position.

A detent is provided to lock the workman's lever *b* in a position to bring the space between the ends of the time-sheet between the platen and time-wheels of the main time-printing mechanism and when the time-sheet is not to be used, an operative connection being provided between this detent and

a door for controlling the card-slot adjacent to the combined printing means. This detent and the operative connection between it and the door for closing the time-card slot 5 consists of a fork the shank 102 whereof is slidable in a slot 103 in the case and the forked end 104 whereof when in its outward position straddles the workman's lever *b*. The inner end of this shank is connected by a cord 105 to a crank-arm 106 upon the end of one of the trunnions of a flap-door 107, adapted to at times close the card-slot 108.

A guard 90, provided with locking means 91, closes the auxiliary slot 75 when piece-work is not to be timed.

The operation of my invention is as follows: When a time-sheet is to be used, it is placed upon the rollers, and upon the workman's lever being swung to its proper angular position on the dial and pressed in the time-sheet will first be returned to its proper position relatively to the printing-wheels and then pressed upon the latter, thus receiving the required impression. If at any time it is desired to use the device in connection with time-cards, the lever should be locked by swinging the detent into engaging position, thus opening the card-slot. Upon the card being then inserted and the lever pressed in the necessary printing will be done upon the card, while at any time simultaneously with the printing of a time-sheet or a time-card on the combined printing means the cards for piecework may be printed upon the auxiliary means.

The advantages attendant upon this invention are that piecework or continuous work can be timed and either cards or time-sheets used by this recorder without making any change or substitution of parts. Furthermore, the time-wheels may be set from the hand of the clockwork when the latter is turned in either direction, owing to the particular construction of my improved means for operating the hour-wheel from the minute-wheel and for retaining the hour-wheel in its proper printing position.

The day-workman register on the time-sheet. The piece-worker coming in at the same time registers on the auxiliary. Special job-work (after all workmen are in and the workman's lever is locked and the auxiliary slot is closed) is timed on the combined mechanism by means of cards.

What I claim is as follows:

1. In a workman's time-recorder comprising, in a single inclosing case, time-printing means, means for supporting a time-sheet in position to receive an impression from such printing means, a time-indicating device for operating the printing means, an auxiliary time-printing means operated by said time-indicating device and means whereby a time-card is supported in position to receive an impression from the auxiliary printing means.

2. In a workman's time-recorder, the combination with a clock-movement, time-printing wheels, and means operatively connecting the clock-movement to the time-printing wheel, of a star-wheel mounted upon one of the printing-wheels to rotate therewith, a notched disk connected to the other of the printing-wheels to rotate therewith, and a fork fulcrumed at its crotch above the latter, one of the legs of such fork having its end bent to engage the notch in the disk, a retractile helical spring retaining such leg out of engaging position, the other leg of the fork having its end bent to present an angular tooth to engage between the points of the star-wheel. 75

3. In a workman's time-recorder, the combination with a clock-movement, minute and hour printing wheels, and means operatively connecting the said clock-movement to said time-printing wheels, of a star-wheel rigidly connected to and rotatable with said minute-wheel, a movable part adapted to be engaged and moved by a part actuated by the workman, a suitably-supported rotatable spindle, a rod secured at one end of said spindle and 90 having its free end bent to extend toward the points of said star-wheel and tapered, a collar rotatably mounted upon said spindle, a bar connected at one end rigidly to said collar, and connected at its other end to and movable with said first-mentioned movable part, a stop limiting the movement of said collar 95 relatively to said spindle, and a spring yieldingly retaining said bar and rod against movement toward one another. 100

4. In a workman's time-recorder, the combination with time-printing wheels of a carrier for a time-sheet, said carrier consisting of a frame pivoted at one end to a stationary part of the recorder, and having its opposite end extending beneath said time-printing wheels, a pair of rollers, one mounted in each end of said carrier, a platen extending parallel to the roller in the free end of said carrier and adapted to be brought into bearing relation with said time-printing wheels when the free end of said carrier is raised, means for connecting a time-sheet to said rollers, means for rotating said rollers, and means for raising and lowering said carrier. 105 110 115

5. In a workman's time-recorder, the combination with time-printing wheels, and the workman's lever, of a carrier for a time-sheet, said carrier consisting of a frame pivoted at one end to a stationary part of the recorder, and having its opposite end extending beneath said time-printing wheels, means for rotatably supporting the time-sheet upon said frame, a platen extending parallel to and beneath said time-printing wheels and 120 carried by said frame, a slid able rod adapted to be slid by said workman's lever when it is moved axially, a lever pivoted beneath the inner end of said slid able rod and extending upwardly across same and adapted to be 125 130

1
moved thereby, a bar extending beneath said pivoted frame, toggle-bars connecting said last-mentioned bar to said pivoted frame, means for supporting said last-mentioned bar constantly in the same horizontal plane, a coiled spring connected at one end to said lever at the upper end of the latter, the other end of said spring being connected to said horizontal bar, a second coiled spring connected at one end to said horizontal bar and at its other end to a stationary part of the recorder.

6. In a workman's time-recorder, the combination with time-printing wheels, of a carrier consisting of a frame pivoted at one end to a stationary part of the recorder, and having its opposite end extending beneath said printing-wheels, a platen extending parallel to and beneath said time-printing wheels and carried by said carrier, and means for raising said carrier and causing said platen to bear upon said time-printing wheels each time said workman's time-recorder is operated.

7. In a workman's time-recorder, the combination with a clockwork, of time-printing wheels, means for supporting said time-printing wheels, means for connecting said clock-movement to said time-printing wheels and rotating the latter, a movable platen, a workman's lever adapted to be swung and depressed, means connecting said lever to said platen whereby said platen will be moved into bearing relation with said time-printing wheels upon the depression of said workman's lever, inking devices for inking the type upon said time-printing wheels, a movable detent for at times preventing the swinging of said workman's lever, the frame of said recorder having a slot in a line with the point between said platen and time-printing wheels, auxiliary time-printing wheels, means connecting the clockwork to said auxiliary time-printing wheels whereby the latter are rotated, a lever fulcrumed adjacent to said auxiliary time-printing wheels and having one arm projecting beneath the latter and its other arm projecting outside of said recorder, a spring yieldingly retaining said lever in a position with its inner arm away from said time-printing wheels, a flexible platen upon the inner end of said inner arm, a guide upon the upper side of said arm, the frame of the recorder having a slot in line with said guide, a slidable bar having one end projecting out-side of the recorder and graduated, a stop upon the inner end of said slidable bar for limiting the extent to which a card may be inserted through said slot and guide.

8. In a workman's time-recorder, the combination with time-printing wheels, of a time-sheet carrier consisting of a pair of rollers arranged a short distance apart and beneath said time-printing wheels, means for connecting a time-sheet to said rollers in band form, means for inking the type of said time-print-

ing wheels and means for raising and lowering one of said rollers toward and from said time-printing wheels.

9. In a workman's time-recorder, a time-sheet carrier consisting of a frame pivoted at one end, a roller rotatably mounted in each end of said frame, each of said rollers having an annular guard near each end thereof, an endless flexible impression-apron stretched around said rollers between said guards, means for securing the time-sheet upon said apron a platen carried by said frame and extending transversely of and beneath the upper portion of said apron, and means for raising and lowering the free end of said frame.

10. In a workman's time-recorder, the combination with the casing thereof and time-printing wheels, of a time-sheet carrier consisting of a pair of rollers arranged a short distance apart and beneath said time-printing wheels, means for connecting a time-sheet to said rollers in band form, means for inking the type of said time-printing wheels and means for raising and lowering one of said rollers toward and from said time-printing wheels the said casing of the recorder having a card-slot in line with the space between said rollers and time-printing wheels.

11. In a workman's time-recorder the combination with a workman's lever, a carrier for a time-sheet, means for connecting said time-sheet to said carrier with a space between the ends of said time-sheet, of means for locking the workman's lever in a position with the space between the ends of the time-sheet in the printing-line of the recorder.

12. In a workman's time-recorder the combination with the time-indicating device, combined time-sheet and time-card printing means and an operative connection between said time-indicating device and said combined printing means, a workman's lever and means operatively connected to said workman's lever for moving said time-sheet relatively to said time-printing means, of means when in one position simultaneously locking the workman's lever against movement and allowing the insertion of a time-card and when in a different position simultaneously allowing the workman's lever to move and preventing the insertion of a time-card.

13. In a workman's time-recorder, the combination with a clockwork, of time-printing wheels, means for supporting said time-printing wheels, means for connecting said clock-movement to said time-printing wheels and rotating the latter, a movable platen, a workman's lever, means whereby said platen will be moved into bearing relation with said time-printing wheels, inking devices for inking the type upon said time-printing wheels, the frame of the recorder having a slot in a line with a point between the platen and the time-printing wheels, auxiliary time-printing wheels, means connecting the clockwork to

the auxiliary time-printing wheels whereby the latter are rotated, the frame of the recorder having a slot in line with the auxiliary printing-wheels for the insertion of a card, 5 and means whereby the auxiliary printing means is caused to make an impression upon the card last mentioned.

In testimony whereof I have affixed my signature in presence of two witnesses.

WILLIAM ARCHIBALD WOOD.
